(57) **CLAIM**

The ornamental design for a mount for rooftop article installation, as shown and described.

DESCRIPTION

FIG. 1 is a front elevational view of a mount for rooftop article installation, showing my new design, the rear elevational view being a mirror image thereof;
FIG. 2 is a right side elevational view thereof;
FIG. 3 is a left side elevational view thereof;
FIG. 4 is a top plan view thereof;
FIG. 5 is a bottom plan view thereof;
FIG. 6 is a right front perspective view thereof; and,
FIG. 7 is a left rear perspective view thereof.
The broken lines represent environmental structure only, and form no part of the claimed design. The dot-dash lines represent the boundaries of the claimed design and form no part of the claimed design.
